UNITED STATES PATENT OFFICE.

JOHN H. WAIT, OF OPELIKA, ALABAMA.

AUTOMATIC RAILROAD-SWITCH.

SPECIFICATION forming part of Letters Patent No. 223,559, dated January 13, 1880.

Application filed November 28, 1877.

To all whom it may concern:

Be it known that I, JOHN H. WAIT, of Opelika, in the county of Lee and State of Alabama, have invented a new and useful Improvement in Automatic Railway-Switches, of which the following is a specification.

Figure 1 is a plan view of my improved switch. Fig. 2 is a side elevation of a truck carrying a switch-operating device. Fig. 3 is a sectional elevation taken on line xx in Fig. 1. Fig. 4 is a detail view of the track-locking device. Fig. 5 is a detail view of the switch-lock. Fig. 6 is a transverse section taken on line yy in Fig. 1. Fig. 7 is a cross-section of the weighted lever.

Similar letters of reference indicate corresponding parts.

The object of my invention is to construct a railway-switch that may be operated by the wheels of the passing locomotive, or by means of levers attached to the locomotive or one of the car-trucks.

The invention consists in a combination of pivoted rails, levers, and locking devices, which are hereinafter fully explained.

In the drawings, A B C D are main-track rails. E E' are switch-rails, pivoted to the ties at a , and connected together by a rod, b , in the usual way. F G are terminal rails of the side track or branch.

The rail C of the main track and the rail G of the branch track are pivoted to the tie H at c , and are connected at their free ends by a tie-rod, d , which holds them parallel to each other.

I is a shaft journaled in supports J K, which are placed at the side of the track opposite the switch-rail E'. Upon the end of the shaft I a lever-arm, e , is placed, which is connected with the free end of the pivoted rail G by the rod f , which runs under the rail D, and is bent twice at right angles and passes through a hole in the rail G from the inside, and is secured by a nut.

A right-angled lever, L, is placed on the shaft I between the supports J K, and near the latter. A rod, g , having formed on it the collar h , is jointed to the arm i of the right-angled lever L, and extends through a hole made in the rail E' near its free end.

A rod, k , is jointed to the arm l of the le-

ver L, and extends through a hole in the rail E', near that through which the rod g passes, and is provided with a head which prevents it from being drawn through the rail. This rod is curved so that the arm l may be thrown into a horizontal position, as shown in Fig. 4. The arms i l of the lever L are arranged in such relation to the arm e that a line drawn centrally through the said arm will bisect the angle formed by the arm i l .

Upon the end of the shaft opposite the arm e a disk, M, is secured. Upon the inner face of this disk, at its periphery, there are two lugs, m n , which are placed apart a distance equal to about one-fourth of the circumference of the disk, and are placed in the same relation to the shaft I as the arms of the lever L.

Between the disk M and the support J a three-armed lever, N, is placed loosely on the shaft I. The shorter arms o p of this lever are arranged at right angles to each other, and form, with the longer arm, q , an angle of one hundred and thirty-five degrees. The longer arm, q , is beveled on each of its edges, being widest on the side lying against the disk, and it carries at its outer end a weight, r .

In the inner face of the disk M there are two conical cavities, s , for receiving the conical end of the bolt t , which is placed in a transverse hole drilled in the support J. A portion of this bolt is reduced in size, forming a shoulder, against which a spring, u , presses, which abuts upon a plate, v , through which the smaller end of the bolt extends.

The bolt t is headed upon the outer face of the plate v , so that when the plate is turned in the recess a' in the support J, in which it is placed and withdrawn by means of the loop or handle w , the bolt is removed from the cavity in the disk M.

When the plate v is placed in the recess a' and turned so that the end having in it the aperture b' projects through a lateral opening, c' , in the support J, a padlock may be placed in the aperture b' , when the bolt cannot be withdrawn by hand.

There is an arc-shaped slot, d' , in the disk M, for receiving a bolt, e' , that passes through the forked end of the connecting-rod f' , which is placed between the arms o p of the lever N and embraces the disk M. The opposite

end of the rod is connected with a piece, N' , which is pivoted between the track-rails to one of the ties.

The piece N' is placed wholly upon one side 5 of the track-center, and is nearest the rails A E', and to its upper surface a wedge-shaped piece, O , is secured, having its point lying in the direction of the pivot of the piece N' .

Upon the support K there is a standard, P, 10 having journal-boxes for receiving the vertical shaft Q. To the lower end of this shaft a slotted arm, g' , is secured, which is moved by a pin projecting from the rod f. To the upper end of the shaft Q a signal-disk, h' , is secured.

15 The pilot-wheels of the locomotive, or the forward truck in the train, carries a lever, R, having the long arm i' and the short arms $j' k'$. To the longer arm i' a bar, l' , having notches $m' n' o'$, is connected. The notches in this bar 20 engage a standard, p' , on the truck. The arm j' is separated a short distance from the long arm i' , and to the short arm k' a toe, q' , is jointed.

Below the lever R there is an arm, s' , which 25 supports the toe when the arm i' is thrown backward, and folds it when the long arm of the lever R is moved forward.

The operation of the switch is as follows: Supposing the switch to be set as represented 30 by the drawings, it will be observed that the pivoted terminal rail G of the branch and the fixed rail F are arranged convergingly in relation to each other, and that their disconnected ends are nearer together than the track-gage by a distance equal to the space through 35 which the switch-rails are moved, and that a truck of any sort having wheels with inside flanges must move the pivoted rail G laterally as it passes over it and the rail F. This lateral motion is transmitted to the arm e on the 40 shaft I through the rod f. The shaft I being turned in this manner, the arms $i l$ of the lever L are thrown over toward the switch-rail E', carrying the rods $g k$ forward through the holes 45 in the rails until the collar h strikes the rail E', causing it to move toward the rail G, and moving the rail E, with which it is connected, toward the rail F. The lug n on the disk M at the same time raises the weighted arm q. 50 Owing to the conical form of the end of the bolt t and of the cavity s in the disk, the bolt is thrown back against the spring u as the disk turns, and as the beveled edge of the arm q comes into contact with the conical end of the bolt the bolt is thrown still farther back, and 55 the said arm passes it.

When the weight r passes the shaft I it falls toward the switch-rail E', and the short arm o engages the eye of the connecting-rod 60 f' , through which the bolt e' passes, thereby moving the pivoted piece N' toward the rail E', so that it will be in position to be engaged by the switch-operating device carried by the engine or one of the cars approaching in the 65 opposite direction.

The locking of the switch-rails is effected by bringing the rod g, arm i, and shaft I into

line. This prevents the switch-rails from moving toward the switching apparatus, while they are prevented from moving in the opposite 70 direction by a spike, a' , driven into the tie.

When the weighted arm q has reached a horizontal position inside the support J the bolt t enters the conical cavity s in the disk M near the lug n, and when turned so as to 75 allow the arm having a hole in it to project through the opening c', and a padlock being inserted in the aperture of the said arm, locks it so that the switch cannot be moved by hand, except by removing the padlock from the plate 80 v and turning and withdrawing the plate from the recess a'. When this is done the lever N may be moved by hand, so as to operate the switch.

When the switch has been moved, as just 85 described, the rails C G are in the position indicated by dotted lines, and the switch-rail E is opposite the rail F, and the rail E' is opposite the rail G, as indicated by dotted lines.

When the engine approaches on the main 90 line and the switch-rails E E' are opposite the branch rails, the flanges of the wheels engage the rail C, thereby moving all of the parts of the switching apparatus in the direction opposite to that just described, bringing 95 the switch into line with the main-track rails, as shown in full lines in the drawings. The signal-disk h' is turned in the manner before described whenever the switch is shifted, so as to indicate in the usual way the position of 100 the switch.

When the engine approaches the switch on the rails A B, and it is desired to run upon the branch, the toe q' is thrown down by moving the lever R by means of the bar l' , and locking it by placing the notch m' on the standard p' . As the engine passes the pivoted piece N' the toe q' strikes the side of the wedge O and moves the piece N' toward the rail E'. This results in turning the disk M by means 110 of the connecting-rod f' and operating the switch in the same manner as it is operated by the rod f; and when the switch is to be moved in the opposite direction by the apparatus carried by the engine the arm j' of the lever R 115 is thrown down into the position shown in Fig. 2, and is retained by placing the notch o' on the standard p' . The arm j' now engages the wedge O by moving along the edge opposite that engaged by the toe q' when the switch-rails are thrown into line with the main track, as shown by full lines in the drawings. The switch-rails E E' are locked in this position by the arm l and rod k falling into line with the shaft I, and by the spike a' , driven into the 120 tie outside of the rail E'. The switch-rails E E' are locked in this position by the arm l and rod k falling into line with the shaft I, and by the spike a' , driven into the 125 tie outside of the rail E'.

Having thus described my invention, I claim as new and desire to secure by Letters Patent—

1. The combination of the shaft I, the crank-arm e, the rod f, the arms $i l$ of the right-angled lever L, and the rods $g k$ with the pivoted rail C of the main track and the pivoted rail G of the branch, connected by the tie-rod 130

d, and with the switch-rails *E E'*, substantially as and for the purpose set forth.

2. The spring-bolt *t*, having a conical end, in combination with the disk *M*, secured to the switch-operating shaft *I*, and having the conical cavities *s*, as herein shown and described.

3. The combination, with the spring-bolt *t*, of a plate, *v*, adapted to the recess *a'* and *c'*, and having the handle *w* and lock-aperture *b'*, as herein shown and described.

4. The pivoted piece *N'*, carrying the wedge-shaped piece *O*, in combination with the disk

M, lever *e*, and the double-armed lever *L*, as herein shown and described. 15

5. The weighted lever *N*, having arms *o p q*, and the disk *M*, having lugs *m n*, in combination, as herein shown and described.

6. The lever *R*, pivoted in a truck, and having arms *i' j' k'*, the toe *q'*, and bar *s'*, in combination, as herein shown and described. 20
